UNITED STATES PATENT OFFICE.

FRIEDRICH WILHELM SCHUBERT, OF APPERLEY BRIDGE, NEAR BRADFORD, ENGLAND, ASSIGNOR TO BRYSLKA, LIMITED, OF APPERLEY BRIDGE, NEAR BRADFORD, ENGLAND.

MANUFACTURE OF ARTIFICIAL SILK.

Application filed June 21, 1926, Serial No. 117,537, and in Great Britain July 2, 1925.

This invention relates to the manufacture of artificial silk by the cuprammonium process and has particular reference to the bobbins, shells or tubes on to which the 5 filaments are wound during the stretch spinning process, the chief object being to provide an improved construction of bobbin which will permit the empty and full shells or tubes being readily changed whilst 10 ensuring of them being firmly held during their rotations in the spinning machine.

According to the invention each bobbin comprises a frame or spider and a shell with 15 means for frictionally holding the shell to the frame or spider when placed in position thereon. In an embodiment of the invention the frame or spider may comprise, two three-armed end pieces with slotted or recessed connecting members or bars between. 20 Into the slots or recesses may be fitted spiral springs which normally tend to expand radially so as to grip the internal periphery of the shell or tube at spaced points. The springs may be fitted with rubber sheaths 25 and the arrangement may be such that as the empty sleeve or shell is placed in position the springs will be compressed within the slots or recesses into the plane of the bars, whilst when the shell or tube is 30 moved they will protrude to form curved or arcuate protuberances.

In order that the invention may be clearly understood and readily carried into effect, the same will now be more fully described 35 with reference to and by the aid of the accompanying drawings; wherein:—

Figures 1 and 2 are respectively a side elevation and transverse section of a bobbin frame or spider fitted with means for frictionally holding a shell in position thereon.

Figure 3 is an end elevation of the frame or spider with a shell in position thereon.

Figures 4 and 5 are respectively an end elevation and longitudinal section of one of 45 the frictional shell retaining means or elements.

Referring to the drawings, the frame or spider comprises two three-armed end pieces 1, connected together by three longitudinally disposed members or bars 2, which are formed with slots or recesses 3, adapted 50 to be fitted with means for frictionally hold-

ing or retaining the cylindrical ebonite or other shell 4, in position, and said frictional holding or retaining means 5, may, as shown 55 more particularly at Figures 4 and 5, each comprise a spiral spring 5^x fitted or encased by a rubber or other flexible sheath or covering 5^y. As shown at Figures 1 and 2, the frictional holding or retaining means 5 tend 60 to expand radially and protrude through the slots or recesses 3, so that when an empty sleeve or shell 4, is placed in position on the frame or spider the spring members 5 are compressed within the said slots or recesses 3 into the plane of the bars 2, as shown at Figure 3, whilst when the shell 4 is removed the said spring members 5 will again protrude to form curved or arcuate 70 protuberances as shown at Figures 1 and 2. 75

The three-armed end pieces 1 are formed with centrally disposed aligned bosses 6, carrying short axles or shafts 7, through the medium of which the bobbin as a whole may be rotatably mounted.

I claim:—

1. A winding bobbin comprising two end pieces, a plurality of bars connecting said end pieces, and each provided with a longitudinally extending recess or slot, and a 80 coiled spring arranged within each said recess or slot and projecting radially therefrom at intermediate points in its length, for the purpose described.

2. A winding bobbin comprising two end pieces, a plurality of bars connecting said end pieces, and each provided with a longitudinally extending recess or slot, and a resilient member normally projecting radially 90 from the recess or slot in each connecting bar, said member comprising a coiled spring enclosed in a flexible cover.

3. A winding bobbin comprising two three-armed end pieces, bars connecting the aligned arms of the head pieces and each 95 having a longitudinally extending recess or slot formed therein, and a resilient member extending longitudinally of each said slot or recess and projecting radially therefrom at intermediate points in its length, 100 each said member comprising a body of rubber like material having a coiled spring embedded therein.

FRIEDRICH WILHELM SCHUBERT.
